SHEET FEEDER

Frank R. Belluche, Racine, Wis.

Application October 28, 1937, Serial No. 171,507

21 Claims. (Cl. 271—55)

This invention relates to sheet feeders for printing machines and the like.

The constant demand for higher operating speeds in printing machinery has imposed stringent requirements upon sheet feeders. This is readily apparent from the fact that it is not unusual now to require a speed of five thousand sheets per hour, even with excessively large sheets.

Many expedients have been proposed and adopted in the past for increasing the speed of operation, but in many instances, increased operating speeds have been obtained only at the expense of accuracy in registration. Registration requires a definite period of time which cannot be reduced without seriously jeopardizing its accuracy, and as past methods of registering the sheet entailed bringing the sheet to rest at the front guides of the press which meant actually stopping the forward travel of the sheet for an appreciable time interval, all devices heretofore proposed for increasing the operating speeds of sheet feeders met the same limiting obstacle which was "time for registration".

With underlapped feeding of the sheets where-in the sheets are advanced to the press in underlapped relationship, time for side registering the sheet was exceptionally short and as proper side registry required a certain time interval regardless of how it was done, this fact definitely limited the amount which the sheets could be overlapped and thus precluded deriving the full benefits of underlapped feeding.

This invention is directed to a correction of these inherent objections to past sheet feeder constructions and has as one of its objects to provide an improved manner of squaring the sheet and also side registering the same so that these two necessary functions can be accomplished while the sheet is in motion, thus obviating the heretofore necessary stopping of the sheet.

More particularly it is an object of this invention to provide means operable on the rear or trailing edge of the sheet as it approaches the press or other machine being fed to square the same and positively move the same to its exact registering position in time to be picked up by the grippers of the press or other machine being fed. This permits the front guide of the press to be entirely eliminated so that the advance of the sheets does not have to be interrupted at any point, and where from the nature of the work, it is desirable to utilize or retain the front guides, the present invention permits the sheet to be presented thereto in such a manner as to entirely

eliminate the possibility of rebound, crumpling of the leading edge, or any other form of improper presentation.

A further object of this invention is to provide gripper means adapted to engage the trailing edge of the topmost of a plurality of underlapped sheets moving toward a final registering position and to so move or actuate the gripper means as to have a differential forward motion which is initially fast to insure proper engagement of the gripper means with the sheet, and then slow to bring the sheet to its final registering position at a speed considerably slower than that of the conveying means which advances the sheets in underlapped relation.

Another object of this invention is to provide a construction of the character described wherein the closure of the gripper jaws is controlled by a cam driven from the motion of the gripper mechanism itself so that the timing of the closure of the gripper jaws is at all times synchronized with the motion of the gripper mechanism.

With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawings illustrate one complete example of the physical embodiment of the invention constructed according to the best mode so far devised for the practical application of the principles thereof, and in which:

Figure 1 is a longitudinal sectional view through a sheet feeder illustrating the application of this invention thereto;

Figure 2 is an enlarged sectional view similar to Figure 1, but showing only the gripper mechanism and its directly associated elements;

Figure 3 is a side view of the gripper mechanism, and illustrating particularly the manner in which its various motions are produced;

Figure 4 is a top plan view of the gripper mechanism and its associated elements; and

Figure 5 is a cross sectional view through Figure 3 on the plane of the line 5—5.

Referring now particularly to the accompanying drawings in which like numerals indicate like parts throughout the several views, the numeral 5 designates a conveyor of any suitable construction, arranged to advance sheets S in underlapped relation toward a predetermined final registering

position with respect to a printing press or other printing machine to be fed. In the present instance, the conveyor is shown as presenting the sheets toward the initial transfer cylinder 6 of a press (not shown) equipped with the customary front guide 7.

The sheets are separated from a source and deposited onto the conveyor 5 in any suitable manner, and the conveyor is driven to continuously move the underlapped sheets toward the press. As the sheets approach the final registering position, the topmost sheet which is the one nearest the press, has its trailing edge engaged by a reciprocating gripper mechanism, indicated generally by the numeral 8, by which the sheet is squared, side registered, and positively advanced to its final registering position independently of the conveyor 5.

The gripper mechanism 8 comprises a plurality of thin edged lower fingers 9 adapted to be moved forwardly against and under the trailing edge of the topmost sheet to lift the same onto their upper surfaces where it is held by gripper jaws 10. All of the lower fingers 9 are journaled on a transverse shaft 11, the ends of which are supported in end frames 12 and 12'. To accommodate sheets of different widths the lower fingers 9 are adjustable on their supporting shaft 11, being held in adjusted positions by U-shaped yokes 13 embracing the fingers 9 and adjustably secured to the shaft 11 by set screws.

Each finger 9 has a rearwardly extending lug 14 which is engageable with the undersurface of its yoke 13 to limit the downward motion of the finger 9 while permitting upward motion thereof. This vertical freedom of the fingers 9 is desirable to permit independency of the respective fingers and insure the engagement of their thin front ends under the trailing edges of the sheets.

The gripper jaws 10 are all mounted on a transverse shaft 15 journaled in bearings carried by the end frames 12 and 12' and disposed substantially directly above the shaft 11. While the gripper jaws 10 are permitted a degree of rotation with respect to the shaft 15, this permitted motion is limited by keys 16 adjustably fitted in an elongated keyway in the shaft and engaging in circumferentially enlarged keyways 17 in the gripper jaws. Any suitable means may be employed to hold the gripper jaws 10 against longitudinal motion along their supporting shaft 15, and in the present instance, collars 18 are detachably secured to the shaft 15 at opposite sides of the gripper jaws.

The permitted relative rotation between the gripper jaws 10 and their supporting shaft 15 allows each gripper jaw to be individually yieldingly urged toward its cooperating finger 9 by a compression spring 19 confined between the adjacent yoke 13 and a lug 19 extending rearwardly from the gripper jaw. This permitted relative rotation between the gripper jaws and their supporting shaft 15, however, is only sufficient to provide the desired individual spring tension so that upon a clockwise rotation of the shaft 15, as viewed in Figures 2 and 3, all of the gripper jaws 10 are lifted off of their fingers 9 to an open position shown in dotted lines in Figure 2.

The outer ends of the gripper jaws 10 carry rollers 20, the peripheral surfaces of which are coated with a suitable substance having a high coefficient of friction, or the entire roller may be composed of rubber or some similar material.

This provides a frictional engagement between the gripper jaws 10 and the top surface of the sheet.

The lower fingers 9 are all notched or recessed to slidably receive a bar 21 against which the sheet is clamped by the rollers of the gripper jaws 10. The top of the bar 21 is flush with the upper face of the fingers 9 and to positively preclude having the sheet catch on the edge of the bar, it has its forward edge slightly beveled. Endwise motion of the bar 21 with a sheet clamped thereagainst by the friction rollers of the jaws 10 draws the sheet sidewise to side register the same. This endwise motion of the bar 21 is obtained in a manner to be hereinafter described.

The necessary stop against which the side edge of the sheets is brought to bear during the side registering thereof, is provided by a side wall 22 on the lower finger 9', which is nearest the end frame 12' and toward which the side registering motion of the bar 21 is made. This wall projects perpendicularly up from the top surface of the finger 9' and the bar 21 moves through a hole therein.

For squaring the sheet, the fingers 9 have aligned shoulders or registering faces 23 to engage the rear or trailing edge of the sheet. To insure proper engagement of the squaring shoulders or registering faces 23 with the trailing edge of the topmost sheet, the initial forward motion of the grippers is faster than the linear speed of the conveyor 5.

After the clamping of the sheet by the gripper jaws 10 so that the sheet is positively held by the gripping mechanism, its advance is at a slower speed with its final forward motion at a speed considerably less than that of the conveyor 5 so that the actual presentation of the sheets to the final registering position is slow.

Reciprocation of the gripper mechanism is produced by a box cam 24 fixed to a cam shaft 25 which is driven from a longitudinal shaft 26 deriving its power from the mechanism of the feeder (not shown). The driving connection between the shafts 25 and 26 is effected through meshing miter gears 27 and 28, the gear 28 being slidably splined to the shaft 26 to permit longitudinal adjustment of the entire gripper mechanism.

Tracking in the box cam 24 is a cam follower 29 which is carried on the lower end of a lever 30, secured to a shaft 31 which is journaled in side frames 32 and 33. These side frames are slidably supported on fixed rack bars 34 and 35, and by sliding the same longitudinally on the bars, adjustment of the entire gripper mechanism to compensate for sheets of different lengths is obtained. Such adjustment of the side frames is facilitated by pinions 36 meshing with the teeth of the rack bars and fixed to a transverse shaft 37 carried by the side frames 32 and 33.

An upwardly extending lever 30' fixed to the shaft 31 is connected to the side frame 12' of the gripper mechanism through a link 38 and the other side frame 12 of the gripper mechanism is connected through a link 39 with the upper end of a lever 40 also fixed to the shaft 31. From this it will be seen that oscillation imparted to the shaft 31 by the box cam 24 rocks the levers 30' and 40 to smoothly reciprocate the entire gripper mechanism.

The gripper mechanism is supported for reciprocation by having its end frames 12 and 12' slidably supported on arms 42 and 43 secured at

one end to a transverse shaft 44. The shaft 44 is journalled in bearings carried by the side frames 32 and 33 and has a lever 45 fixed thereto outwardly of the side frame 33. The free end of this 5 lever carries a cam follower 46 which tracks on a cam 47 fixed to the cam shaft 25. The shape of the cam 47 is such that it holds the arms 42 and 43 parallel with the top of the conveyor 5 for a period of time long enough to encompass the full 10 forward stroke of the gripper mechanism and to lift the arms at the limit of the forward stroke so as to raise the gripping mechanism off the top of the sheets and hold the same in such raised position until the retraction of the gripping 15 mechanism has been completed.

As noted hereinbefore, the gripping jaws 10 are raised or opened by oscillation of their supporting shaft 15. Such motion is imparted to the shaft 15 by a cam 48 fixed to a stub shaft 49 journalled 20 in the end frame 12'. Riding on the cam 48 is a cam follower 50 carried on the outer end of a lever 51 which is keyed to the shaft 15. The throw of the cam 48 is such that the required oscillation is imparted to the shaft 15 to rock the 25 same sufficiently to lift the gripper jaws 10 off their respective fingers 9.

The motion of the cam 48 is derived from the reciprocation of the gripper mechanism on its supporting arms 42 and 43, through a pinion 52 30 fixed to the shaft 49 and meshing with a rack 53 cut along the bottom of the arm 43. The pitch diameter of the pinion 52 with relation to the shape of the cam 48 and the stroke of the gripper mechanism is such that the gripper jaws 10 are 35 held in their elevated or open positions throughout the entire return stroke of the gripper mechanism, and also during the initial forward motion of the gripper mechanism to permit engagement of the gripper fingers 9 with the trailing edge 40 of the topmost sheet into full contact with the registering faces or shoulders 23. After such squaring engagement between the shoulders or faces 23 with the trailing edge of the sheet, the cam 48 allows the gripper jaws 10 to be closed 45 down onto the sheet.

The shape of the box cam 24 is such that the initial forward motion of the gripper mechanism is faster than the linear speed of the conveyor 5 to effect the proper engagement of the gripper 50 mechanism with the trailing edge of the topmost sheet and is increasingly slower toward the end of its forward stroke so as to present the sheet to its final registering position at very slow speed. The retraction of the gripper mechanism by the 55 box cam 24 is preferably rapid.

Endwise motion of the bar 21 to effect side registry of the sheet is also derived from the reciprocation of the gripper mechanism through the medium of a barrel cam 55 fixed to the shaft 60 49. Engaging in the groove 56 of the barrel cam is a cam follower 57 secured to the bar 21 so that upon rotation of the cam endwise motion will be imparted to the bar 21.

The shape of the cam groove 56 is such that 65 during the forward stroke of the gripper mechanism, the bar 21 remains stationary until the sheet has been gripped and thereafter the bar is moved toward the end frame 12' to draw the sheet into engagement with the registry face formed by the 70 inner surface of the wall 22. At the limit of the forward stroke of the gripper mechanism the barrel cam rotating in the opposite direction returns the bar 21 to its initial position.

While the embodiment illustrated discloses the 75 presentment of the sheets to the front guide of a

press, it will be readily apparent that inasmuch as the sheet is under positive control at the time of its arrival at this position, and as it has been completely registered, the front guide may be entirely omitted so that the forward advance of the sheets may be continuous and uninterrupted. 5

From the foregoing description taken in connection with the accompanying drawings, it will be readily apparent to those skilled in the art to which this invention appertains, that this invention makes possible higher operating speeds without sacrificing accuracy of registration as it allows a comparatively long period of time to be devoted to the registration of the sheet, and that the invention has the further advantage of allowing for 10 a greater overlap of the sheets which permits a 15 slower sheet advance.

What I claim as my invention is:

1. In a sheet feeder for printing machines and the like, the combination of: conveying means 20 for advancing sheets along a defined path for presentment to the machine; and means movable along said same path in the direction of the sheet advance and at a speed slightly in excess of that of the sheet advance for engaging the trailing 25 edge of the sheet nearest the machine and operable to present the sheet to the machine and effect registration thereof prior to its presentment to the machine.

2. In a sheet feeder: conveying means for conveying sheets in underlapped relationship toward a registering position; gripper means engageable with the trailing edge of the sheet nearest said registering position, said gripper means having registering faces engageable with the rear edge 35 of the sheet to square the sheet; and means for actuating said gripper means to impart first a fast motion in the direction of sheet advance and in excess of the speed of the sheet to insure engagement of its registering faces with the rear 40 edge of the sheet, and then a retarded motion slower than the speed of the conveying means so as to present the sheet to its registering position at slow speed.

3. In a sheet feeder: conveying means for advancing sheets in underlapped relationship toward a registering position; and movable means to grip the trailing edges of the sheets as they approach the registering position to control the final advance of the sheets to said registering 50 position; and means carried by said movable means for acting on the sheets to square and side register the same while they are in motion toward said registering position.

4. In a sheet feeder: conveying means for advancing sheets toward a final registering position; movable sheet gripping means adapted to engage and grip the trailing edge of a sheet nearest said registering position to carry the sheets to said final registering position independently 60 of the conveying means; squaring shoulders on the gripping means engageable with the trailing edge of the sheet when the gripping means is fully engaged with the sheet; and actuating means for said gripper means operable to move the same 65 in the direction of sheet advance at a speed greater than that of the sheets to effect engagement of the gripper means with the trailing edge of a sheet to square the same.

5. In a sheet feeder: conveying means for advancing sheets toward a predetermined position; movable gripper means engageable with the trailing edge of a sheet nearest said position, said gripper means positively holding the sheet against any motion thereof by said conveying 75

- means; and means for actuating the gripper means to present the sheet held thereby to said predetermined position independently of said conveying means and at a linear speed less than 5 that of said conveying means.
6. In a sheet feeder: conveying means for advancing sheets in underlapped relationship toward a predetermined position; a reciprocating gripper means movable above the sheets on said 10 conveying means and engageable with the trailing edge of the topmost sheet, said gripper means having registry faces to engage the trailing edge of the sheet and having means to securely grip the sheet and hold it against motion by said 15 conveying means; and means for actuating said gripper means to have first a forward motion at a speed in excess of that of the conveying means to insure engagement of its registry faces with the trailing edge of a sheet, and then a 20 slower forward motion so as to present the sheet to said predetermined position at a speed less than that of the conveying means.
7. In a sheet feeder: conveying means for advancing sheets in underlapped relationship toward a predetermined position; a reciprocating gripper means movable above the sheets on said 25 conveying means and engageable with the trailing edge of the topmost sheet, said gripper means having registry faces to engage the trailing edge of the sheet and having means to securely grip the sheet and hold it against motion by said conveying means; means for actuating said gripper means to have first a forward motion at a speed in excess of that of the conveying means to insure engagement of its registry faces with the trailing edge of a sheet, and then a slower forward motion so as to present the sheet to said 30 predetermined position at a speed less than that of the conveying means; and means for controlling the gripping action of the gripper means so that the sheet is gripped directly after engagement of the registry faces therewith.
8. In a sheet feeder: conveying means for advancing sheets in underlapped relationship toward a predetermined position; reciprocating gripper means disposed above said conveying means and engageable with the trailing edge of the topmost sheet; means for reciprocating said gripper means with a successive fast and slow 35 forward motion in the direction of sheet advance and a rapid return motion; and means for lowering the gripper means onto the sheets at the limit of its return stroke and for lifting the gripper means after it has engaged the trailing 40 edge of the topmost sheet and advanced the same to said predetermined position.
9. In a sheet feeder: conveying means for advancing sheets in underlapped relation toward a predetermined position; gripper means having 45 cooperating jaws to clamp a sheet therebetween; means for reciprocating the gripper means above the conveying means in proximity to the trailing edge of the topmost sheet; means for raising and lowering the gripper means as it reciprocates to cause the same to engage the trailing edge of 55 the topmost sheet; and means for controlling the closure of the jaws of said gripper means so as to hold the same open until proper engagement of the gripper means with the trailing edge 60 of the sheet has been effected.
10. In a sheet feeder: conveying means for advancing sheets toward a predetermined position; means reciprocating above said conveying means and adapted to grip the trailing edge of 65 the sheet nearest said predetermined position by moving fast enough to overtake said trailing edge of the sheet, said reciprocating means having registering faces to bear against the trailing edge of the sheet to square the same; and means carried by said reciprocating means for side registering the sheet as it is moved by the reciprocating means toward said predetermined position. 5
11. In a sheet feeder: conveying means for advancing sheets toward a predetermined position; a reciprocating gripper mechanism disposed above said conveying means and having a forward motion in the direction of sheet advance to be engageable with the trailing edge of a sheet nearest said predetermined position, said gripper mechanism having a differential forward speed 10 to move quickly at a speed in excess of that of the conveying means into engagement with the rear edge of a sheet and then complete its forward motion at a speed slower than that of the conveying means; means for controlling the 15 gripping action of said gripper mechanism to insure proper engagement of the sheet therewith prior to positive gripping of the sheet; and means for effecting side register of the sheet while it is in the grip of said gripper mechanism. 25
12. In a sheet feeder: conveying means for advancing sheets toward a predetermined position; reciprocating gripper means disposed above said conveying means and having a forward stroke in the direction the sheet is advanced by 30 the conveying means, said gripper means having a registering face and jaws to clamp a sheet therebetween; cam means for reciprocating the gripper means with a variable forward speed which is initially faster than the speed of the conveying means so that the gripper means overtakes the trailing edge of the sheet nearest said predetermined position and then slower than the speed of the conveying means; and means for controlling the clamping jaws of the gripper 35 means to hold the same open during the initial forward motion of the gripper means and until engagement of its registering face with the trailing edge of the sheet nearest said predetermined position and to maintain engagement of the 40 clamping jaws with the sheet for the remainder of the forward advance of the gripper means so that the sheet is presented to said predetermined position by the gripper means at a speed slower than that of the conveying means. 50
13. In a sheet feeder: conveying means for advancing sheets in underlapped relationship toward a predetermined registering position; means engageable under the trailing edge of the topmost sheet to lift the same; means for moving 55 the lifting means forwardly toward said registering position with the sheet in engagement therewith; and means carried by said lifting means and operable upon a sheet engaged thereby for side registering the same while it is in 60 motion toward said registering position.
14. In a sheet feeder: sheet conveying means for advancing sheets in underlapped relation toward a predetermined registering position; gripper means above the conveying means, said gripper means having registering faces; means for actuating said gripper means to impart a reciprocating motion thereto and to engage the same with the trailing edge of the topmost sheet so that its registering faces abut the trailing edge 65 of the sheet to square the same; and side registering mechanism movable with the gripper means and operable on the sheet to side register the same while it is in motion toward said predetermined registering position. 70
- 75

15. In a sheet feeder: conveying means for advancing sheets in underlapped relationship to a predetermined registering position; a plurality of grippers having registering faces and disposed above said conveying means to be engageable with the trailing edge of the topmost sheet; means for reciprocating the plurality of grippers in unison to advance a sheet engaged thereby to said predetermined registering position independently of the conveying means; means for lowering the grippers in unison into operative relationship with the trailing edge of the topmost sheet and to lift the grippers off the sheets; and means for controlling the gripping action of said grippers to insure the engagement of their registering faces with the trailing edge of a sheet prior to gripping the same.
16. In a sheet feeder: conveying means for advancing sheets in underlapped relationship to a predetermined registering position; a plurality of grippers having registering faces and disposed above said conveying means to be engageable with the trailing edge of the topmost sheet; means for reciprocating the plurality of grippers in unison to advance a sheet engaged thereby to said predetermined registering position independently of the conveying means; means for lowering the grippers in unison into operative relationship with the trailing edge of the topmost sheet and to lift the grippers off the sheets; means for controlling the gripping action of said grippers to insure the engagement of their registering faces with the trailing edge of a sheet prior to gripping the same, and side registering means operable upon the sheet being carried by the grippers for effecting side register thereof while it is in motion toward said predetermined registering position.
17. In a sheet feeder: a reciprocating gripper mechanism to grip a sheet and move it; means for side registering the sheet while it is being moved by the gripper mechanism; and means positively driven from the motion of the gripper mechanism for actuating the side registering means.
18. In a sheet feeder: a reciprocating gripper mechanism to grip a sheet and move it; means for side registering the sheet while it is being moved by the gripper mechanism including a member movable sidewise with respect to the sheet and adapted to cause sidewise motion of the sheet; and motion producing means positively driven by the reciprocation of the gripper mechanism for actuating said member.
19. In a sheet feeder: a reciprocating gripper mechanism to grip a sheet and move it; means for side registering the sheet while it is being moved by the gripper mechanism including a member movable sidewise with respect to the sheet and adapted to cause sidewise motion of the sheet; a cam for actuating said member; a gear for driving the cam, said gear being carried by the gripper mechanism to move therewith; and a rack meshing with the gear and along which the gripper mechanism moves so that reciprocation of the gripper mechanism drives said cam.
20. In a sheet feeder: a reciprocable gripper; means for reciprocating the gripper to engage the same with a sheet; said gripper having a movable jaw; cam means for controlling said movable jaw and determining the time of closure of the gripper; and means deriving motion from the reciprocation of the gripper mechanism for actuating said cam means.
21. In a sheet feeder: conveying means for advancing sheets along a defined path; means movable along said same path at a speed slightly in excess of that of the sheet advance so as to overtake the trailing edges of the sheets; and means carried by said last named means for gripping and registering the sheets during advance of the sheets subsequent to the engagement of said means with their trailing edges.

FRANK R. BELLUCHE.
